UNITED STATES PATENT OFFICE.

HARRIET L. GALBRAITH, OF WASHINGTON, DISTRICT OF COLUMBIA.

HEATING DEVICE.

1,011,608.

Specification of Letters Patent. Patented Dec. 12, 1911.

Application filed February 11, 1911. Serial No. 808,048.

To all whom it may concern:

Be it known that I, HARRIET L. GALBRAITH, citizen of the United States, residing at Washington, in the District of Columbia, have invented certain new and useful Improvements in Heating Devices; and I do hereby declare the following to be a full, clear, and exact description of the invention, such as will enable others skilled in the art to which it appertains to make and use the same.

My invention relates to heating devices which are adapted to be used in connection with the heating means, such as steam radiators for houses, apartments and hospitals for purposes of cooking, or for heating water, sterilizing or analogous uses, and consists of certain new and useful improvements in the same, whereby the heater may be removably connected with the radiator, when desired, and which during the heated period of the year, may be disconnected therefrom, and used with a steam supplying vessel, in which the water is heated by means of a gas or other form of heater.

One of the objects of my invention is to provide a simple and inexpensive means for conducting the heating medium, such as steam, from the radiator to the heater, in such a manner that the gas, air or steam which issues from the relief valve of the radiator, will be prevented from passing through the heater, but will be allowed to escape into the atmosphere, in the usual manner, thus obviating a very serious objection which exists in devices of this character, heretofore constructed, and in which the escaping gas, air or steam from the radiator passes through the heater.

Another object which I have in view, is to make it possible to use such a heater, in connection with the usual form of radiator, without altering the latter and without interfering in any manner with its normal operation.

In order that my invention may be clearly understood, I have illustrated it in the accompanying drawing, which is a side elevation of a radiator and heater, in the form of a cooker, provided with my improved connecting means, and I have described the same with reference thereto in the following specification and claims.

A of the drawing represents a radiator, of usual construction and B a cooker, adapted in my preferred form to rest upon the

radiator. I prefer to place the cooker as shown for the reason that by doing this heat from the radiator will be communicated to the cooker and will many times serve to keep articles of food at the temperature desired without the admission of steam to the interior of the cooker.

a is a relief valve of any ordinary construction, with which a radiator is provided, and is for the purpose of allowing the escape of gas or air from the radiator.

The connecting means between the radiator and the cooker, through which steam is admitted to the cooker, comprise the T coupling D, which is adapted to be removably connected at one end to the steam radiator and at the other end with the relief valve *a*, and other elements, as follows: Intermediate the ends of the coupling D there is secured thereto a pipe E connected to another pipe *c* by means of a joint *c*². The outer end of the pipe *c* is tapered, and is adapted to enter an opening *b* in the side of the heater or cooker. The pipe *c* is provided with an ordinary valve, operated by a handle *c'*.

The manner of applying and using my invention is obvious. In my preferred form of construction, I locate the supplemental cooker on top of the radiator. The valve *a* is then removed from the radiator and the part D secured in place. The valve *a* is then placed upon the part D and the other parts of the connecting means assembled and secured to the part D in the usual manner. The end of the pipe *c* is then inserted in the supplemental heater or cooker, after which the heating medium may be admitted to the supplemental heater, the supply being controlled by the valve in the pipe *c*. By this construction it will be noted that the action of the relief valve *a* in connection with the radiator is not interfered with, and the action of the radiator is exactly the same as though the heater was not connected therewith.

It is obvious that the connecting tubes may be made of various lengths, so as to be used with different forms and sizes of radiators.

What I claim and desire to secure by Letters Patent is:—

1. A cooker for use with a steam radiator having an outlet passage provided with a relief valve for the escape of air or gas, the said cooker comprising a main body or cas-

- ing for holding articles to be heated or cooked, and pipe connections for conveying steam from the radiator to the cooker, said connections containing a valve to control the passage of steam therethrough, and adapted to be connected with the outlet passage to the relief valve to permit the operation of the relief valve and cooker independently of each other.
- 10 2. A cooker for use in connection with a steam radiator, comprising a main body or casing for holding articles to be heated or cooked, and a connection for supplying said casing with steam, said connection being adapted to be connected with the radiator between the escape or relief valve and the radiator, said connection being provided with a valve or cock to control the admission of steam to the said casing.
- 15 20 3. A cooker for use in connection with
- a steam radiator, comprising a main body or casing for holding articles to be heated or cooked, pipe connection between said main body and radiator for supplying steam to said main body, said connection having one end connecting with the interior of said casing and having its other end adapted to be connected with the radiator between the escape or relief valve and the radiator, said pipe connection being provided with a valve or cock permanently connected therewith for controlling the admission of steam to said casing.

In testimony whereof I affix my signature, in the presence of two witnesses.

HARRIET L. GALBRAITH.
